UNITED STATES PATENT OFFICE.

ARTHUR CAUTIUS, OF TILSIT, PRUSSIA, GERMANY.

OIL-LAMP WITH ANNULAR BURNER.

SPECIFICATION forming part of Letters Patent No. 401,543, dated April 16, 1889.

Application filed January 10, 1888, Serial No. 260,270. (No model.) Patented in England October 8, 1887, No. 13,664; in France October 17, 1887, No. 186,432; in Belgium October 18, 1887, No. 79,241, and in Spain May 5, 1888, No. 7,887.

To all whom it may concern:

Be it known that I, ARTHUR CAUTIUS, of 5 Tilsit, in the Kingdom of Prussia and German Empire, have invented a new and useful Improvement in Oil-Lamps with Annular Burners, of which the following is a specification, reference being had therein to the accompanying drawings.

The invention herein described has been 10 patented to me elsewhere as follows: In Great Britain October 8, 1887, No. 13,664; France, October 17, 1887, No. 186,432; Belgium, October 18, 1887, No. 79,241, and Spain, May 5, 1888, No. 7,887.

15 This invention relates to that class of oil-lamps in which the oil burns in the interior of the annulus formed by the wick and burner, giving a ring flame.

The object of my invention is to provide an 20 oil-tight joint between the oil-reservoir and the burner, so that the oil cannot escape even when the lamp is upset. This I attain by means of the mechanism shown in the accompanying sheet of drawings, in which—

25 Figure 1 is a longitudinal section of the improved lamp reservoir and burner constructed according to my invention. Fig. 2 is a sectional elevation of adjusting mechanism. Fig. 3 is a section on line $x-x$ of Fig. 2. 30 Fig. 4 is a horizontal section of the plug or stopper for closing reservoir.

The same letters refer to the same parts in all the figures.

35 a is a central tube rigidly connected with the oil-reservoir b , air being admitted to same by means of slots c .

d is the wick, which is pressed against the outer tube, e , by means of springs h , so as to move with it. Said tube has at its extremity 40 an internal flange, f , said flange being bored to accurately fit the tube a .

By means of the mechanism hereinafter described the tube e is capable of being moved up and down with reference to the tube a , 45 thereby regulating the height of the burning portion of the wick, (shown at g .) When the tube e is lowered to its fullest extent, the flange f fits over the end of the tube a , and thus extinguishes the flame.

50 The mechanism for raising and lowering the tube e consists of the tube i , which carries at its extremities screw-threads, one of which, k , serves to screw the burner into the

reservoir, while the other, l , supports the gallery. The tube e is capable of moving up 55 and down in the tube i , and has attached to it two pins, n , taking into diametrically-opposite slots m in the tube i . Over this tube i is placed another short tube, o , fitted with an adjusting-disk, o' , (shown in the drawings 60 as forming a part of the tube o .) The whole being capable of a motion of rotation on the tube i , longitudinal motion being prevented by means of the cap q and disk p , forming a part of or secured to the tube i . This tube 65 is also provided with two diametrically-opposite slots, r , also engaging with the pins n . The slots r being oblique, on rotating the disk o' in one or other direction, the position of the pins n in the said slot is altered, and the tube 70 e being moved up and down by the said pins the light is thus regulated or extinguished. The tube i is provided with a rim, s , made of thin metal, which bears against the tube e , forming a tight joint between the tubes i and 75 e , preventing any leakage of oil should the lamp be upset. To allow of the reservoir being filled and to provide for the egress of air from the same when screwing in the burner, or to allow ingress of air as the oil is consumed, I provide a screw-cap, t , fitted with a valve, v , closed by means of a spring, w , placed between the valve v and the bridge-piece x .

To allow any compressed air to escape from the reservoir, the valve v is opened by pressing the stud y ; but should a vacuum be produced in the reservoir, owing to consumption of oil by the flame, the valve v opens automatically and allows air to enter. Lamps constructed on this principle may be burned 90 for some weeks without cleaning.

What I claim, and desire to secure by Letters Patent of the United States, is—

A lamp consisting of a central tube, a , the wick-tube, e , provided with projecting pins, 95 the tube i , encircling the tube e and slotted, as described, the tube o , having inclined slots engaging with the pins of the tube, the cap q and disk p , and the hand-disk o' , for rotating the tube o , substantially as described. 100

In witness whereof I have hereunto set my hand in presence of two witnesses.

ARTHUR CAUTIUS.
